UNITED STATES PATENT OFFICE

2,573,086

SCAFFOLD BRACKET

Watson T. Yoshimoto, Sr., Honolulu, Territory
of Hawaii

Application July 26, 1949, Serial No. 106,807

3 Claims. (Cl. 304—14)

1

My invention relates to improved scaffold brackets, especially but not exclusively, for use on concrete wall forms, the primary object of the invention being to provide, in brackets of this kind, means for mounting the brackets on horizontal wales of the concrete wall forms in such manner that both sidewise rocking movement and vertical rocking movement of the brackets relative to the forms under service conditions are precluded, whereby the safety and efficiency of the resulting scaffolding is greatly increased.

Another important object of the invention is the provision of scaffold brackets of the above indicated character which have relatively great strength and rigidity along with light weight and compactness, and which can be easily manufactured in a serviceable and attractive form at relatively low cost.

Another important object of the invention is to provide scaffold brackets of the character indicated above which include means for efficient use of rope or other flexible guard rails, which are safer and more satisfactory than rigid wood or metal guard rails.

Other important objects and advantageous features of my invention will be apparent from the following description and accompanying drawings, wherein for present purposes of illustration only, specific embodiments of the invention are set forth in detail.

In the drawings:

Figure 1 is a fragmentary perspective view showing a single scaffold bracket applied to a concrete wall form having two adjacent horizontal wales, with the rope guard rails shown in dotted lines.

Figure 2 is a top plan view of a scaffold bracket.

Figure 3 is a side elevation thereof.

Figure 4 is a side elevation of a guard rail post.

Figure 5 is a front elevation thereof.

Figure 6 is a view similar to Figure 1, showing another embodiment of scaffold bracket for use with a concrete wall form having a single horizontal wale.

Figure 7 is a top plan view of the spacer block used with the bracket shown in Figure 6, and

Figure 8 is a side elevation of the spacer block.

Referring to the drawings in detail, the numeral 10 generally designates a concrete wall form side member composed of horizontal planks or boards 11 with laterally spaced vertical studs 12 secured to the outer side thereof, and with vertically spaced horizontal wales 13, 13 secured on the outer edges of the studs, in a generally conventional arrangement. My novel scaffold

2

bracket, generally designated 15 and shown in Figures 1 to 5, consists of a generally right triangular form preferably made of light-weight adequately strong metal tubing with the components 5 full-welded together. The bracket 15 comprises the vertical member 16, long enough to more than reach vertically across two adjacent horizontal wales 13, 13, the horizontal member 17 long enough to reach from a point behind a wale 13 to 10 the proper distance away from the side of the wall form 10 to support thereon the desired width of platform forming planks 18. The horizontal member 17 being welded to the upper end of the vertical member 16 at a point near the inward 15 end thereof, as indicated at 19. A diagonal brace 20 is welded to the lower part of the vertical member 16 at 21 and to an outer part of the horizontal member 17 at 22. The post of the vertical member 16 below the weld 21 is provided with 20 one or more holes 23. The inward end of the horizontal member 17 has welded thereto at 24 a short vertical anchor element 25 and welded at 26 to the outward end of the horizontal member 16 is a vertical guard rail post mounting socket 27. 25 The anchor element 25 and socket 27 and the vertical member 16 are parallel and are preferably arranged in the same vertical plane.

An important feature of the bracket 15 is the inverted horizontal metal channel 28 which is 30 positioned against the underside of the horizontal member 17 in the space between the vertical member 16 and the depending part of the anchor element 25 and welded in place, at right angles to the vertical and horizontal members. The channel 28 extends equally at opposite sides of the horizontal member 17, as shown in Figure 2, and is just wide enough to snugly receive the upper wale 13 between its depending side flanges 29 and 31, with its web 31 resting upon the top of the 35 wale; and with the lower part of the vertical member 16 resting against the outer face of the subjacent wale 13, as shown in Figure 1. The arrangement is such that when the bracket 15 is installed it is self-positioning in the correct perpendicular and parallel relationship to the form 40 10.

The channel web 31 and the side flanges thereof are provided with holes 32 and 33, respectively, to accommodate preferably duplex head nails 34 50 to secure the channel in proper engagement with the upper wale 13. A similar nail may be used in the hole 23 to secure the lower part of the vertical member to the face of the subjacent wale 13, if desired.

55 The socket 27 is provided with one or more

threaded holes 35 to accommodate wing bolts 36 to lock in place the related safety rail post 37. The rail post 37 consists of a tube of the desired vertical length having secured in its lower end a reduced portion 38 which depends therefrom and is of substantially the same inside diameter as the socket 27. The portion 38 is traversed by vertically spaced holes 39 to receive the locking bolt 36 whereby the post 37 can be rigidly and securely mounted in correct position in the socket 27, at different heights. In its most depressed position the shoulder 40 at the upper end of the portion 38 rests upon the upper end of the socket 27 for additional support.

The upper end of the post 37 has a transversely arranged upstanding loop or eye 41 to accommodate an upper flexible guard rope 42 and a lower loop or eye 43 is secured on the outward side of the post to accommodate a lower guard rope 44, as shown in Figure 1.

The spacer block 50 comprises a truncated isosceles triangular form of flat uniform width rigid metal bar on strip, having the base side 51 thereof indented, as indicated at 52, to provide two feet 53 at the ends thereof. The converging ends of the sides 54, 54 of the triangular form are prolonged in parallelism as indicated at 55, 55 and are rigidly connected together by a bridge part 56 containing a hole to accommodate the assembling bolt 57. The prolongations 55 are spaced to snugly receive the lower part of the vertical bracket member 16 therebetween, and the bolt 57 is arranged to pass outwardly through the hole 23 in the vertical member 16a and receive a wing nut 58 on its outer end to clamp the spacer block on and in proper relation to the bracket 15 with the feet 53 engaging flush with the form planks 11, as shown in Figure 6.

It will be understood that as many of the above described brackets as desired may be used at the desired distances from each other along the concrete form when erecting or stripping the form.

What I claim is:

1. A scaffold bracket comprising a right triangular frame comprising a horizontal platform plank supporting member and a vertical member depending from said horizontal member at a point spaced from the inner end of said horizontal member, a horizontal inverted channel secured to said horizontal member at a point between said vertical member and the inner end of said horizontal member, abutment means on the lower end of said vertical member comprising a spacer block positioned at the inward side of said vertical member, and means removably securing said spacer block in place on said vertical member, said spacer block comprising an open form having laterally spaced prolongations receiving the vertical member therebetween, a bridge part connecting said prolongations having a bolt extending therefrom between said prolongations and removably passing through a hole provided in said vertical member, and a nut on said bolt bearing against the outward side of said vertical member and securing said

spacer block to extend horizontally from said vertical member.

2. In a scaffold bracket, a triangular frame comprising a horizontal member having inner and outer ends, a vertical member depending from said horizontal member at a point spaced from the inner end of the horizontal member, and a downwardly facing channel member secured crosswise to the underside of said horizontal member at a point between the inner end of the horizontal member and said vertical member, said horizontal member having a vertically extending anchor member on its inner end, said anchor member having a lower portion depending along the inward side of said channel member, said anchor member having an upper portion rising above said horizontal member and said horizontal member having a vertical element on its outer end rising thereabove, said upper portion of the anchor member and said vertical element serving as inner and outer stops for planks placed upon said horizontal member therebetween.

3. In a scaffold bracket, a triangular frame comprising a horizontal member having inner and outer ends, a vertical member depending from said horizontal member at a point spaced from the inner end of the horizontal member, and a downwardly facing channel member secured crosswise to the underside of said horizontal member at a point between the inner end of the horizontal member and said vertical member, said horizontal member having a vertically extending anchor member on its inner end, said anchor member having a lower portion depending along the inward side of said channel member, said anchor member having an upper portion rising above said horizontal member and said horizontal member having a vertical element on its outer end rising thereabove, said upper portion of the anchor member and said vertical element serving as inner and outer stops for planks placed upon said horizontal member therebetween, said vertical element being tubular for reception of a guard rail post.

WATSON T. YOSHIMOTO, SR.
